Attorney

UNITED STATES PATENT OFFICE.

VERNA DE LAIN, OF WYMORE, NEBRASKA.

LOCKING DEVICE FOR SPOUTS.

Application filed April 27, 1927. Serial No. 186,993.

The present invention relates to a device for locking the delivery spout of a railroad water supply tank in a lowered position so that the spout cannot swing upwardly.

5 Due to the pressure of the water as the same passes from the tank through the delivery spout, the spout has a tendency to raise upwardly, and as a result, considerable difficulty is experienced by a fireman on an 10 engine in properly holding the spout while taking water. It is therefore an important object of the present invention to provide a simple and efficient means whereby the spout may be locked in a lowered operative 15 position, thus obviating the necessity of the fireman having to hold the delivery spout while taking water.

A still further object of the invention is to provide a locking device of the above 20 mentioned character which may be readily and easily attached to the spout and the mast which extends vertically at the side of the water tank, without necessitating any material alterations of the parts of the water 25 tank with which the locking device is to be associated.

A further object is to provide a locking device of the above mentioned character which is simple in construction, inexpensive, 30 strong and durable and further well adapted to the purpose for which it is designed.

Other objects and advantages of the invention will become apparent from the following description taken in connection with 35 the accompanying drawings.

In the accompanying drawings wherein like numerals indicate corresponding parts.

Figure 1 is a fragmentary side elevation of a railroad water supply tank, the upper 40 portion of the mast being illustrated and the locking device embodying my invention being shown attached to the delivery spout with the parts so arranged as to maintain the spout in a lowered position.

45 Figure 2 is a front elevation of the upper portion of the mast showing the manner in which the guide rod is supported between the uprights comprising the mast.

Figure 3 is a sectional view taken approximately 50 on the line 3-3 of Figure 1 looking in the direction of the arrows for more clearly disclosing the locking device.

Figure 4 is a side elevation of a saddle forming a part of the present invention.

55 Figure 5 is a sectional view taken approxi-

mately on the line 5-5 of Figure 1, and Figure 6 is a detail perspective view of the locking bolt.

In the drawings wherein for the purpose of illustration is shown the preferred embodiment of my invention, the numeral 1 designates a water supply tank which is supported on the frame 2 in the manner well known in the art. An outlet pipe 3 extends from the bottom of the tank 1 and associated with the outer end of this pipe is the delivery spout 4. Extending vertically at the side of the frame and tank 1 adjacent the spout 4 is the usual mast designated generally by the numeral 5, the same comprising the vertically spaced standards or uprights 6 and 7, respectively.

The parts thus far described are of the conventional construction and it is therefore thought unnecessary to further go into detail with respect thereto.

A bearing carrying strap 8 is secured transversely across the upper ends of these standards or uprights 6 and 7, the bearing being designated by the numeral 9. A similar cross piece 10 is disposed transversely across the lower portions of the standards at a point above the inner end of the spout 4 as is clearly shown in Figures 1 and 2 of the drawings and the bearing associated with this cross member is designated by the reference character 11. The bearings 9 and 11 provide a means for supporting the respective ends of a vertically disposed guide rod 12, and a purpose of this guide rod will 90 be presently described.

Slidable on this guide rod 12 is the head 13, the upper end portion thereof being bifurcated to form the parallel spaced arms 14 and 15, respectively, and the bifurcated upper end portion of the head is disposed laterally as is clearly illustrated in Figures 1 and 5 of the drawings. The bottom portion of the head 13 is formed with an opening for a purpose to be hereinafter more 100 fully described. A grooved pulley 16 is supported between the arms 14 and 15 on a transverse pin 17 and this pulley is adapted to engage the guide rod 12 in the manner also as clearly shown in Figure 5. A 105 bolt 18 extends through suitable registering openings provided therefor in the outer ends of the arms 14 and 15 and a nut 19 is threaded on the threaded end of the bolt, the bolt being disposed on the opposite side 110

of the guide rod 12, thus preventing the displacement of the head member from engagement with the rod.

Also forming an important part of the present invention is a saddle 20 which is curved to conform to the contour of the delivery spout 4 on which the saddle is to be mounted and for the purpose of securing the saddle on the spout, the saddle is formed at its side edges with the strap members 21 and 22, two pairs of such strap members being provided and these strap members are also curved to conform to the contour of the delivery spout 4 and the free ends of the opposed straps are disposed laterally as at 23 and a bolt 24 extends through suitable registering openings provided therefor in the laterally disposed free ends of each pair of straps 21 and 22. A nut 25 is threaded on the threaded end of the bolt and in this manner the straps can be securely clamped around the spout to support the saddle 20 in a rigid position on the top of the spout. The specific manner in which the saddle is secured on the spout is more clearly disclosed in Figure 3 of the drawings.

Formed on the top of the saddle and extending upwardly therefrom is the longitudinally extending bar or relatively thick plate 26, the rear or inner end portion of which extends for a greater height than the forward end portion. A hook 27 is formed at the upper forward edge portion of this bar or fixed plate 26 and the purpose of this hook will also be presently described.

An arcuate shaped slot 28 is formed in the rear upper portion of the upwardly projecting bar or fixed plate 26 and an opening 29 is also formed in the rear end portion of this bar or plate directly below the arcuate shaped slot 28 in the manner clearly disclosed in Figure 4 of the drawings.

A lower head member 30 has its lower end portion bifurcated to provide parallel spaced arms 31 and 32 respectively, and these arms straddle the upwardly projecting bar or fixed plate 26 in the manner shown very clearly in Figure 3. The upper portion of the head member 30 is formed with an internally threaded socket into which is threaded the lower end of an elongated rod or arm 33, the upper end of which is threaded into the socket provided therefor in the bottom of the upper head member 13. Suitable lock nuts 34 and 35 are associated with the lower and upper threaded ends of the rod 33 and engage the respective head members for preventing the accidental displacement of the rod from engagement with the upper and lower head members. This rod provides an operative connection between the upper head member 13 which is slidable on the guide rod 12 and the lower head member

30 as is readily obvious from the construction shown in Figure 1.

A pivot forming bolt 36 extends through suitable registering openings provided therefor in the free end portions of the arms 31 and 32 of the bifurcated head member 30 and through the opening 29 provided in the rear end portion of the bar or fixed plate 26, and this construction provides a means whereby the lower head member 30 is adapted for vertically swinging movement with respect to the saddle 20.

The arm 31 is provided with an elongated slot 37 adjacent the inner end thereof as clearly shown in Figure 3, and disposed within this slot is the substantially rectangular shaped head 38 formed on one end of the bolt 39 which is of a suitable length and which has its other end threaded as at 40. The bolt 39 extends through the arcuate slot 28 formed in the upper rear end portion of the bar 26, and through a suitable opening provided therefor in the other arm 32 of the bifurcated head 30 as is also clearly shown in Figure 3.

A stationary cam 41 is secured on the threaded outer end of the bolt 39 by the nuts 42 and this cam 41 is spaced from the outer face of the arm 32 of the head member 30. A notch 43 is formed in this cam 41 as is clearly shown in Figure 3. Adapted for cooperation with this cam 41 is the cam sleeve 44 which is adapted for rotation on the bolt 39 between the arm 32 and the stationary cam 41. The cam forming outer end of this sleeve 44 is also notched as illustrated at 45 for cooperation with the notched portion 43 of the stationary cam 41 and when the parts are arranged as shown in Figure 3, the head member 30 is free to swing in a vertical plane over the curved upper edge portion 46 of the upstanding bar or fixed plate 26.

A lever 47 extends laterally from the sleeve 44 and is provided for the purpose of actuating the sleeve. When the lever 47 is swung in one direction, the sleeve 44 will be rotated about the bolt 39 and during the rotation of the sleeve the cammed outer end of the sleeve will cooperate with the stationary cam 41 to cause the bolt 39 to move outwardly whereby the inner face of the head 38 will be brought into binding engagement with the adjacent face of the bar or fixed plate 26, thus securing the head member 30 in a locked position against swinging movement with respect to the saddle.

This action takes place when the spout 4 is swung to a lowered operative position, whereby the spout will be locked in such position against upward swinging movement, while water is being taken from the tank.

For the purpose of assisting in returning the delivery spout 4 to its upwardly raised

inoperative position after a sufficient amount of water has been taken from the tank there is provided a chain 48 which is looped over the hook 27 formed at the forward end of the upstanding bar 26 on the saddle 20. The free end portions of the chain are disposed over suitable pulleys 49 which are supported on a shaft 50 which is disposed between the upper ends of the standards 6 and 7 of the mast 5, and a counterweight 51 is attached to the free end portions of the chain in the manner clearly shown in Figure 2. Manifestly when the head 38 on the bolt 39 is out of binding engagement with the bar or fixed plate 26, the spout 4 may be swung upwardly and during the upward swinging movement of this spout, the upper head 13 will slide upwardly on the guide bar 12 and the weight 51 will support the spout in its raised inoperative position.

Furthermore, this chain and hook provides a means for preventing the accidental dropping of the delivery spout, thereby preventing any possibility of a person being injured by the fall of the spout.

It will thus be seen from the foregoing description that I have provided a locking device for securing the delivery spout of a railroad water supply tank in a lowered operative position, thus obviating the necessity of a fireman having to hold the spout while taking water. The simplicity of my improved locking device enables the same to be readily and easily actuated, and the same will at all times be positive and efficient in carrying out the purpose for which it is designed.

While I have shown the preferred embodiment of my invention, it is to be understood that various changes in the size, shape and arrangement of parts may be resorted to without departing from the spirit of the invention and the scope of the appended claims.

Having thus described the invention, what I claim is:—

1. In combination with a mast, and the vertically swinging delivery spout of a railroad water supply tank, of a saddle secured on the spout, a vertically swinging head member connected to the saddle, an addi-

tional head member adapted for vertically slidable movement on the mast, interconnecting means between the head members, and cooperating means between the lower head member and the saddle for locking said pivoted head member against vertical swinging movement to hold the spout in a lowered position.

2. In combination with a mast, and the vertically swinging delivery spout of a railroad water supply tank, of a saddle secured on the spout, a vertically swinging head member connected to the saddle, an additional head member adapted for vertically slidable movement on the mast, interconnecting means between the head members, and cooperating means between the lower head member and the saddle for locking said pivoted head member against vertical swinging movement to hold the spout in a lowered position, said last mentioned means comprising a camming headed bolt carried by the pivoted head member and adapted for binding engagement with the saddle.

3. In combination with a mast, and the vertically swinging delivery spout of a railroad water supply tank, of a saddle secured on the spout, an upstanding bar formed on the saddle, a lower head member pivotally mounted on said bar and adapted for vertical swinging movement, an upper head member adapted for slidable movement on the mast, a rod interconnecting said head members, said lower head member being bifurcated, the arms thereof straddling the bar, one of the arms being formed with an elongated slot, the bar being formed with an arcuate slot, a headed bolt extending through the arm and through said arcuate slot, the head of the bolt being disposed within said slot in said arm, and camming means associated with the other end of the bolt for moving the head of the bolt into binding engagement with the bar to lock the lower head member against vertical swinging movement and hold the spout in a lowered position.

In testimony whereof I affix my signature.

VERNA DE LAIN.
